FIRING MECHANISM

William Summerbell, Washington, D. C., Louis J. Rhein, Aberdeen, Md., and Owen D. Hoopes, Arlington, Va.; Edith May Summerbell executrix of said William Summerbell, deceased

Application July 10, 1945, Serial No. 604,286

4 Claims. (Cl. 89—27)

(Granted under the act of March 3, 1883, as amended April 30, 1928; 370 O. G. 757)

1

The invention described herein may be manufactured and used by or for the Government for governmental purposes, without the payment to us of any royalty thereon.

This invention relates to firing mechanisms.

A purpose of the invention is to provide a firing mechanism for artillery employing separate loading ammunition and in which a separate primer is used to ignite the propellant charge each time the gun is fired.

Another purpose of the invention is to provide a simple and convenient means of inserting into and removing a primer cartridge from the breech mechanism of a gun.

A further purpose of the invention is to provide a means of automatically removing the fired primer cartridge.

An additional purpose of the invention is to provide a firing mechanism which prevents the escape of gases through the firing mechanism.

Another purpose of the invention is to provide a means of applying a uniform and predetermined degree of firing pin impact against the primer cartridge regardless of the amount of force applied to the firing lanyard, and for cocking and firing the mechanism upon a continuous pull of the lanyard.

Other purposes and advantages of the invention will become apparent from the following description of a preferred device embodying the invention and the drawings thereof in which:

Figure 1 is a face view of the device in firing position;

Figure 2 is a face view of the device with open breech;

Figure 3 is a side sectional view of the device taken upon a plane indicated by the line 3—3 of Fig. 1;

Figure 4 is a plan view taken along line 4—4 of Figure 3 and partly in section to indicate the internal structure of the movable housing;

Figure 5 is a sectional view taken along line 5—5 of Figure 3;

Figure 6 is a sectional view taken along line 6—6 of Figure 3;

Figure 7 is a side elevational view of the firing mechanism, the view being partly broken out along line 7—7 of Figure 4;

Figure 8 is a detail longitudinal sectional view of the firing hammer and firing spring stop taken in a plane indicated by line 8—8 of Fig. 10;

Figure 9 is an end view looking from the right, Fig. 8.

Figure 10 is a detail top view of the firing hammer and firing spring stop;

2

Figure 11 is a face view taken along line 11—11 of Figure 7, showing only the surfaces nearest line 11—11;

Fig. 12 is an exploded perspective view of the hammer and trigger assembly and their housing.

Fig. 13 is a section taken upon a plane identified by the line 13—13, Fig. 3, and

Fig. 14 is an enlarged sectional view of a portion of Fig. 3.

10 As will be more fully explained below, the present invention provides a firing mechanism, no part of which needs to be removed from the gun to remove a fired primer or to insert a new primer in preparation for again firing the gun. The 15 firing mechanism may, for convenience of description, be considered as having several main mechanical operations or operating parts which in turn cooperate to cause the mechanism to function as a unitary whole.

20 Thus, there is the function or operation of ejecting the fired primer cartridge. There is the operation of opening and closing the breech of the firing mechanism which is accomplished mainly by lowering or raising the movable breech 25 block of the mechanism. There is the operation of firing the primer by a continuous pull on the lanyard, thus cocking the mechanism, retracting the driving spring and then releasing it so it can cause the striker to actuate the firing pin, firing the primer.

30 There is provision for automatically adjusting the primer head space and in which the mechanism will not move to firing position until the head space is properly adjusted, thereby guarding against damage caused by improper head-space.

In addition there is provision for providing a standardized impact against the primer regardless of the force used in retracting the lanyard, and also provision for allowing the cocking lever to which the lanyard is attached, to be rotated to any one of a number of angular positions throughout a complete circle so the direction of pull of the lanyard may be thus adapted to the 40 gunner's needs.

Reference is now had to the drawings in which there is a breechblock carrier indicated generally at 10 and designed for carrying a breechblock for closing the breech end of a gun barrel bore. An obturator spindle 12 has a central flash passageway 14 leading at its forward end, not shown, to the inside of the breech end of the barrel bore of the gun where the separate loading propellant charge is normally placed.

55 The spindle 12 extends rearwardly through a

central bore 16 (Fig. 4) in carrier 10, said bore 16 being enlarged at 18 and further enlarged at 20. A firing mechanism housing 22, generally circular in external contour, is located in bores 18 and 20, a substantially annular adapter ring 24 being employed to take up the otherwise empty space which, in some guns, may remain in bore 20 outside of the housing 22. The adapter ring 24 is split at 23 and is secured to carrier 10 by means of screws 25.

The obturator spindle 12 has external threads 26 at its rearward end 28 which engage the enlarged threaded forward portion 30 of central bore 32 of housing 22, said portion 30 being located in the forward portion 33 of housing 22.

The housing 22 has a reduced outside diameter at 34, thus forming with bore 18 of carrier 10 a substantially annular chamber 36 in which is located a compression spring 38. The housing 22 being threadably secured to the rearward end of obturator spindle 12 which is necessarily slightly movable longitudinally upon firing the gun, is thus slidably located in bore 18.

An obturator spindle plug 40, having an enlarged shoulder or collar 42 is threaded at its forward end 44 into a recess 46 in the rearward end of obturator spindle 12. An annular copper gasket 48 is located between the forward end of plug 40 and the inner forward end of recess 46 for effecting a tight seal against gases escaping around the outside of plug 40. The flat surfaces of the washer 48 are also engaged and pressed into by circular projections V-shaped in cross-section in the abutting surfaces of plug 40 and recess 46 which further enhance the sealing effect of the washer 48 as clearly illustrated in Fig. 14. The further details of construction of spindle plug 40 and its baffle member 50 are described in detail in our copending Patent 2,428,398, dated October 7, 1947.

The central bore 32 of housing 22 is reduced at 52 for receiving the shoulder 42 of plug 40, and is further reduced at 54. The rearward portion 56 of plug 40 extends through the bore 54 but does not touch the walls of the bore, thus leaving an annular recess 58 between the walls of bore 54 and portion 56 of the plug 40 in which is slidably located a primer holder and extractor 60 which is generally a hollow cylinder in shape.

The extractor 60 has an enlarged central bore 62 which slopes inwardly from locations 64 to 66, thereby conforming to the external contour of rearward portion 56 of plug 40. Extractor 60 is provided with an upwardly projecting key 68 which slides in a keyway 70 formed in the corresponding portion of bore 54. The bore 62 slopes outwardly from locations 66 to 72, forming a sloping support for the corresponding surface of the rim of a primer cartridge 73 to be inserted therein, the primer 73 extending into the central bore 74 of plug 40. The primer 73 is firmly rammed into the bore 74 by means of pressure exerted on it by face plate 76 which is carried into the position shown in Figure 3 by means which will be described below.

By examination of Figure 3, it will be noted that a portion of the primer 73 also rests on the reduced rearward end surface 78 of spindle plug 40. Thus, to be sure that there is no looseness or play of the primer cartridge 73 between those abutting parts, including face plate 76, which are to support it in place, the spindle plug 40 must be properly located as shown in Figure 3 which shows the position of the various parts for correct head-

space. Thus the shoulder 42 of plug 40 must be in contact with the surface 80 of bore 52.

To be sure that the spindle plug 40 is properly positioned before the gun can be fired, a head space safety member 82 (Figs. 3 and 6) is provided. The member 82 is generally cylindrical in shape, having an enlarged cylindrical upper portion 84, a converging portion 86 with sloping sides, and a reduced cylindrical lower portion 88. 10 The safety member 82 is slidably disposed in a vertical recess 90 formed in housing 22 and extends radially inward from the housing circumference to location 92 where it intersects with and opens upon keyway 70. The round recess 90 has 15 vertical upper side walls extending from locations 94 to 96, which are slightly longer than the vertical length of portion 84 of safety member 82. The recess then slopes inwardly from locations 96 to 98 and then is cylindrical again but only large 20 enough to allow reduced portion 88 of safety member 82 to pass through. As may be seen in Figure 6, the safety member 82 will, if unsupported, drop until its sloping portion 86 is in contact with the sloping portion of recess 90 extending from locations 96 to 98, at which time the lower portion 88 of the safety would be extending downwardly into keyway 70 and would thus be in the way of and prevent the movement through the keyway, of key 68 on extractor 60, as may also be 30 seen in Figure 3.

Hence it is apparent that for the extractor 60 to move as far forwardly against spindle plug 40 as is necessary, its key 68 must not be obstructed by portion 88 of safety 82, that is, the safety 82 must be elevated to the position shown in Figures 3 and 6 so portion 88 does not extend into keyway 70 at all.

To elevate portion 86 to the requisite height, the relative dimensions of safety member 82 and 40 shoulder 42 of spindle plug 40 are so arranged that when the corner 100 of shoulder 42 bears against sloping portion 86 of safety 82 it raises the safety portion 88 out of keyway 70 only when the spindle plug is in correct location as shown 45 in Figure 3 for proper headspace.

As shown in Figure 3, headspace safety 82 has a recess 102 in which is disposed a compression spring 104 which has its lower end pressing down on the base of recess 102 and its upper end confined by plug 106 which is threaded into the upper enlarged portion 108 of recess 90. The effect of spring 104 is to continuously press safety member 82 downward. Thus, if spindle plug 40 is moved forwardly, and extractor 60 is retracted to the rear, safety 82 is pressed downward into keyway 70 and prevents the key 68 and hence the extractor 60, from moving forward. If the extractor 60 cannot move forward, as will be further explained below, it will prevent moving the face plate 76 and its firing pin into firing position and the gun cannot then be fired. The construction just described is covered by our copending divisional application, Serial Number 76,742, filed February 16, 1949, for Firing mechanism.

65 The face plate 76 is carried by a movable firing lock housing or body 110 carried on housing 22 and which acts as a small breechblock. A pin 77 serves to secure plate 76 to housing 110. The housing 110 carrying the elements comprising 70 the firing assembly, is arranged for reciprocal movement between the firing position shown in Figure 1, and the position shown in Figure 2 where the fired primer has been extracted and the primer chamber is uncovered. The rearward portion of the housing 22 has a central vertical

channel 112 in which the forward portion 114 of housing 110 fits for guided vertical movement. Channel 112 has generally vertical ribs 128 and 130 which slidably fit corresponding grooves 124 and 126 in housing 110.

As illustrated in Figure 7 in connection with groove 126 and its rib 130, all grooves and ribs are inclined downwardly and rearwardly. The result is that as movable housing 110 is dropped from the firing position shown in Figures 1, 3 and 7, to the open position shown in Figure 2, the housing 110 is also moved rearwardly by these inclined guide members.

As shown in Figures 3 and 7, face plate 76 has a sloping surface at 132 which cams the primer 73 into its desired location with its head supported by the extractor and by the end surface 78 of the spindle plug, and its cylindrical sides rammed firmly into the bore 74 as illustrated. As the primer 73 is thus cammed into position, the same pressure presses the extractor 60 into its forwardmost position.

A firing pin 134 is slidably disposed in a firing pin bore 136 extending through face plate 76 and rearwardly through a portion of movable housing 110. The rearward portion of said bore is reduced at 138, providing a stop for engaging collar 140 on the firing pin and preventing the rearward motion of the firing pin beyond the position shown in Figure 3. The rearward end 142 projects into a recess 144 in housing 110. A firing pin spring 146 serves to yieldingly maintain firing pin 134 in retracted position except when momentarily driven forward when struck by the nose 148 of hammer 182, the reduced forward end 150 then moving forward and striking the primer 73, firing it.

The extractor 60 is provided with two lugs 152 (see Fig. 5), the forward surfaces 154 of which are in slidable contact with cam surfaces 156 on movable housing 110, as seen in Figure 7. When the gun is fired, and the housing 110 is dropped from the position shown in Figure 1 to that shown in Figure 2, the lugs 152 are cammed rearwardly by the sloping portion 158 of cam surfaces 156, causing the extractor to be sharply moved rearwardly, thus throwing out or ejecting the fired primer cartridge 73 through the U-shaped passageway 160 formed in the upper surface of movable housing 110. The lugs 152 strike against the sloping surface 132 on movable housing 110 thus preventing the extractor from being ejected along with the fired primer cartridge.

As particularly illustrated in Figure 3, the movable housing 110 has a generally cylindrical recess 164 axially aligned with the bore 136 containing the firing pin 134. The recess 164 has a forward reduced portion 166 into which the rearward end 142 of the firing pin 134 projects. The recess 164 also has an intermediate slightly enlarged portion 168 and a rearward threaded portion 170 slightly larger in diameter than portion 166. A locking cap 170 is threaded into portion 168 and serves to close the recess 164 at its rearward end. The cap 170 has both a projecting rib 172 and a surface slot 174 so it may be turned by hand, or with the aid of either a pliers gripping the rib or a screwdriver or coin inserted into the slot. The locking cap 170 has a recess 176 formed in its inner face in which is seated the rearward end of a firing spring 178, the forward end of which extends into a recess 180 formed in a hammer or striker 182, and bears against the rearward face of a firing spring stop 184. As is seen in the detail drawings in Figures 8, 9 and 10, the

hammer 182 has an enlarged rearward portion 186 smoothly fitting recess 166 and a forward portion 188 smoothly fitting recess 144. The forward portion 188 of hammer 182 is cut away at 190 and 192, forming two parallel side surfaces for a portion of its length so that two openings 194 and 196 are made in the forward end of recess 180. The stop 184 has two forward extensions 198 and 200 extending through the openings 194 and 196, which are long enough to extend forwardly beyond the nose 148 of hammer 182.

It will thus be noted in Figure 3 that the firing spring 178 is constantly under compression between cap 170 and stop 184, the forward ends of extensions 198 and 200 being normally held against the forward end surface 208 of recess 144. It will also be noted that there is normally some clearance between the nose 148 and the rearward end 142 of the firing pin 134.

20 A bore 212 closed at its forward end by a plug 217 is formed in movable housing 110 parallel to and laterally offset from recess 164. The bore 212 contains the forward portion of a trigger assembly, the rearward portion of which extends rearwardly out of said bore as shown in Figure 3. The trigger assembly has the function of retracting the hammer 182 and the firing spring stop 184, the firing spring 178 being thereby compressed against cap 170. After the spring is thus compressed to a suitable degree, the trigger assembly releases the spring 178 to force the firing spring stop 184 and the hammer 182 forwardly toward the firing pin 134.

25 A pull rod 214 has its forward end enlarged and divided into a fork or clevis 216 between the prongs of which is pivotally arranged a firing hammer tripper 218, the pivot pin being located at 220. A bushing 222 is carried by the forward end of pull rod 214, keeping it centered in bore 212. The inner bore of bushing 222 is reduced at its rearward end 224 so as to prevent forward movement of the bushing 222 past the shoulder 226 formed on pull rod 214. A hollow bushing-like member 228 is threaded into the rearward end of bore 212 at 230 and has a central bore 232 in the reduced forward portion 234 of which the rearward portion of pull rod 214 is slidably disposed.

30 The bore 232 is enlarged at 236 and further enlarged at 238. A bushing 240 has its forward reduced portion 242 slidably disposed in bore 236 and its rearward portion 244 slidably disposed in bore 238.

Bushing 240 has a bore appreciably greater 35 in diameter than the adjacent rearward portion of pull rod 214, said bore being enlarged at 246 to loosely receive an annular washer 248 through which the rod 214 extends. The rod 214 is prevented from pulling forwardly out of washer 248 by any suitable means such as a cotter pin passing transversely through a hole in its rearwardly protruding end. Or the end of rod 214 may have a transverse pin and the washer 248 may be formed with a transverse slot in 40 which the end of rod 214 may seat. A compression coil spring or pull rod spring 250 serves to exert pressure between the bushing 222 and the bushing 228.

The bushing 240 is forked at its rearward end, 45 being divided into two rearward extensions 252 between which a cocking lever or firing trigger 254 is pivotally arranged on a pivot pin 256 extending through matching transverse apertures bored through both extensions 252 of bushing 240 and the stud 258 formed on trigger 254.

The firing trigger 254 has a rounded projection, the end 255 of which is in any one of a number of radial slots 257 formed in the rearward face of bushing 228, and the trigger 254 also has an opposite elongated arm 253 to which a lanyard is secured through a loop 251.

The bore 212 of body 110 has an enlarged forward portion 213, a sloping inner surface 215 connecting the enlarged forward bore 213 with the rest of bore 212. As will be explained, the sloping surface 215 serves as a cam for tilting the firing hammer tripper 218 into release position. The tripper 218 has its forward end or foot 219 bearing against and in sliding contact with the inner surface of bore 213 as indicated in Figure 3. The rearward end or finger 260 of tripper 218 extends into bore 166 through a slot 262 which connects bores 164 and 212, as shown, a longitudinal slot 223 being cut entirely through one side of bushing 222 to allow end 260 of tripper 218 to pass through the slot.

When the tripper 218 is in its forwardmost position as shown in Figure 3, its rearward end 260 bears against the sloping surface 210 of hammer 182. As the lanyard attached to arm 253 of trigger 254 is pulled rearwardly, the effect is to retract the pull rod 214 together with the tripper 218. The tripper being in contact with firing hammer 182 at sloping surface 210, causes the hammer 182 and stop 206 to be retracted, compressing firing spring 178. As the rearward movement of the tripper continues, the end 219 of the tripper is carried against sloping surface 215 which cams the end 219 upwardly. This camming causes the tripper 218 to be partly rotated counterclockwise on pivot 220, causing end 260 to move out of bore 166 and into slot 262. Since end 260 is thus no longer in contact with surface 210 of the hammer 182, the spring 178 forces the hammer and the stop 206 forwardly. The forward motion of the stop 206 is arrested by contact of its forward ends 204 with surface 208 of recess 144. However, the firing hammer 182 continues its forward motion, its forward end 202 striking against the firing pin 134, forcing same forward and firing the primer 73. End 269 of bushing 222 continuously presses shoulder 291 on tripper 218 forwardly. When the lanyard attached at 251 is released, the pull rod spring 250 presses the trigger parts into their forward position again as shown in Figure 3. Lubrication may be accomplished through a hole as at 181 or, if desired, the parts may be made self-lubricating as in oilless bearings and the like.

The movable housing 110 is raised into firing position and lowered out of firing position by means of an operating handle or lever 263 rotatably mounted on a pivot pin 264 passing through aligned bores formed in said lever 263 and in the two side walls 265' and 266' of a bifurcated extension of projecting portion 270 of housing 22. If desired, the portion 270 may be made removable in any suitable manner, such as by forming a dovetail-shaped elongated groove or recess 113 in the abutting side face of stationary housing 22 into which an elongated dovetail-shaped extension 272 of projection 270 is inserted and secured therein by means of a pin or set screw 274 passing through the extension 272 and the walls of the groove 113, and keying them together.

The lever 263 has an extension or arm 276 the outer end surface 278 of which is curved on an arc drawn with the pivot pin 264 as a

center. The abutting side of movable housing 110 has a recess 280 formed therein, the surface portion 282 of which has the same curvature as surface 278. A stud 284 formed on the forward face of the outer end of arm 276 extends into recess 280. Thus, when the handle 263 is given a clockwise movement around pivot 264 from the position shown in Figure 1 to that shown in Figure 2, the stud 284 is given a similar motion within recess 280, first riding against the arcuate surface 282 of the recess, and then breaking contact with surface 282 and bearing downward against the surface 286 of recess 280. This downward pressure causes the movable housing 110 to move downward to the position shown in Figure 2 which is the lower limit of movement allowed for housing 110. To raise the housing 110 to firing position shown in Figure 1, the lever 263 is given a counterclockwise rotation about pivot 264, being returned to the position shown in Figure 1.

The degree of angular rotation of handle 263 and arm 276 may be limited in any suitable manner such as by means of spring pressed rounded projections 277 and 279 secured to wall 268' and adapted to enter a matching recess formed in the abutting face of arm 276 so the movement of the arm 276 is between projections 277 and 279. The arm 263 is then rotated from position of Figure 1 to that of Figure 2, and back again, the respective positions being easily and automatically limited in this manner as the matching recess receives and engages either projection 277 or 279.

The angle of trigger 254 may be changed by rotating it to be parallel with any desired slot 257, the arm 253 being pressed forwardly to lift the projection out of the slot 257 prior to rotation to a new slot. This feature is of particular utility in permitting the gunner to change the angular position of the trigger arm 253 for maximum ease in pulling the lanyard from any desired location, and permits him to take advantage of whatever cover is available.

To prevent firing the primer until the breech block of the gun is fully closed, a safety slide 266, carried by the breech block carrier 10, is slidably arranged in a groove or recess 268 formed in carrier 10, and is under constant spring pressure biasing its rounded L-shaped end 269 against the side 270 of movable housing 110. As the movable housing 110 is dropped down from the position shown in Figure 1 to that shown in Figure 2, the end 269 of the safety slide 266 then presses against the sloping surface portion 272 of the housing 110, sliding in groove 268 to keep in contact with the housing. By structure not shown, the safety slide 266 is locked in the position shown in Figure 2 so long as the breech block of the gun is not fully closed. Thus, while the breech block of the gun is open and the firing mechanism is in the position shown in Figure 2, it is possible to insert a primer into the extractor 60, but the movable housing 110 cannot be raised into firing position until the breechblock of the gun is fully closed. The firing mechanism is thus provided with an effective safety feature.

For preventing the cap 170, as shown in Figure 3, and the bushing member 228 from accidentally unscrewing out of the housing 110, the construction illustrated in Figure 11 is employed. This shows a view taken along the line 11-11 of Figure 7, showing only the surfaces nearest to the line 11-11. Thus the radial face 229 of

bushing 228 is undercut outside of the star-shaped portion enclosed by the lines 231, each of the latter lines being an arc of a circle having the same diameter as that of the rearward face of cap 170, and so located that any arc 231, when moved into the position of arc 233, will be in substantial contact all along its arc with the perimeter of cap 170, a small amount of clearance being present. In assembling the parts, the cap 170 is first threaded all the way into its recess until its rearward face is flush with the rearward surface 111 of movable housing 110. The bushing 228, carrying the trigger assembly, is then threaded into its recess all the way, and then turned out again a fraction of a turn until one of the arcs 231 is in the position 233. Then the cap 170 is turned to the left so it backs out of its recess about a turn. In this position, the bushing 228 cannot be rotated due to obstruction from cap 170 and is thus locked in place. The cap 170 cannot accidentally move forwardly out of engagement with the arc 233 because of the rearward pressure of spring 178. Similarly cap 170 cannot move rearwardly due to obstruction of undercut face 229 which overlaps the edge of cap 170.

Although the invention has been described in specific terms, it is to be understood that numerous changes may be made in the dimensions, shapes, materials and arrangement within the spirit and scope of the invention as claimed.

We claim:

1. In a firing device, a housing, a firing hammer reciprocable in said housing, a pull rod axially reciprocable in said housing, means responsive to axial reciprocation of said pull rod in one direction to retract and subsequently release said hammer, a bushing carried by said housing coaxial of said rod and having circumferentially-spaced radial slots, a trigger lever, a swivel connection between the end of said pull rod extending through said bushing and said lever intermediate its ends, and spring means urging said rod in a direction opposite to said one direction to seat one end of said lever in a selected one of said slots.

2. In a firing device for a cannon, a housing having first and second adjacent parallel bores, a firing hammer reciprocable in said first bore, a first spring urging said hammer forwardly into firing position, a bushing fixed with said housing coaxial with said second bore, a pull rod reciprocable in said second bore and extending through said bushing, said bushing having a plurality of circumferentially-spaced slots radial of said rod, means responsive to rearward reciprocation of said pull rod to first retract and then release said hammer, a trigger lever swiveled intermediate its ends to the pull rod adjacent said bushing, one end of said lever being shaped to engage in a selected one of said slots, whereby

said pull rod may be reciprocated by said lever in a plurality of angularly related positions thereof radially of said pull rod.

3. In a firing device, a housing, a hammer movable in said housing, means carried externally by said housing and having a plurality of circumferentially-spaced depressions therein concentric of an axis, a pull rod reciprocable in said housing in and along said axis and extending to the exterior of said housing, a trigger lever, a swivel connection between said lever intermediate its ends and the extending end of said rod, a spring urging said rod forwardly to seat one end of said lever in one said depression, and means operated by reciprocation of said rod in response to a pull on the other end of said trigger lever against the action of said spring, to first move and then release said hammer, said lever being rotatable about the axis of said rod to position its said one end in any selected one of said depressions.

4. In a firing mechanism for cannon, a housing, a pull rod axially reciprocable in said housing and having one end extending exteriorly of said housing, a bushing secured in the wall of said housing concentric of said pull rod, said bushing having a counterbore through the rear face thereof and a plurality of circumferentially-spaced radial slots concentric of said rod, a sleeve fitting the counterbore of said bushing and having an inwardly-flanged forward end, said one end of said rod having a transverse pin seated on the rear face of said flanged end, a trigger lever, a pivot pin passing through aligned holes in said lever and sleeve, spring means urging said rod forwardly to seat one end of said lever in any one of said slots, and means responsive to reciprocation of said rod in response to a pull on the other end of said lever, to fire said cannon.

WILLIAM SUMMERBELL.

LOUIS J. RHEIN.

OWEN D. HOOPES.
